PRESSER FEET FOR SEWING MACHINES

Ludwig J. Kuhar, Clark Township, N.J., assignor to The Singer Manufacturing Company, Elizabeth, N.J., a corporation of New Jersey

Application August 30, 1957, Serial No. 681,229

4 Claims. (Cl. 112—235)

The present invention relates to a presser foot for sewing machines and more particularly to a so-called chaining presser foot which includes a pivoted presser foot and an independently mounted chaining foot that, when the work in the machine has passed the needle, will operate to hold the enchain threads against the feed dog to provide for feeding the chain past the point of stitch formation.

The objects of the present invention are to provide a chaining presser foot that is economical, dependable, durable, and efficient in operation. In accordance with the present invention these objects have been attained by the provision of a chaining presser foot in which there is a single common pivot for both the main sole plate and the chaining foot and in which the chaining foot also has limited bodily movement relatively to the main sole plate in its normal operating range, i.e., during chaining, so that it will remain flat relatively to the feed dog, and wherein there is a single spring that serves not only to bias the chaining foot bodily, but also serves to bias both the chaining foot and main sole plate pivotally about their common axis when the presser foot is lifted from the work.

Having in mind the above and other objects that will be evident from an understanding of this disclosure, the invention comprises the devices, combinations and arrangements of parts as illustrated in the presently preferred embodiment of the invention which is hereinafter set forth in such detail as to enable those skilled in the art readily to understand the function, operation, construction and advantages of it when read in conjunction with the accompanying drawing in which:

Fig. 1 is a fragmentary sectional view transversely of a sewing machine having a presser foot embodying the present invention.

Fig. 2 is a fragmentary sectional view similar to Fig. 1 but taken substantially centrally of the presser foot.

Fig. 3 is a fragmentary sectional view similar to Fig. 2 but illustrating the presser foot per se in the position it assumes when it is raised from the work.

Fig. 4 is a detail sectional view taken substantially on the line 4—4 of Fig. 1.

With reference to the drawing, there is illustrated a sewing machine bed 1 having at the point of stitch formation an opening that receives the usual throat plate 2. A feed bar 3 carries feed dogs 4 which operate through slots, such as 5, in the throat plate 2 to feed the work. Overhanging the bed 1 is the head 6 of the machine in which is slidably mounted for endwise reciprocation a needle bar 7 carrying a needle 8 at its lower end. The throat plate 2 is provided with a needle aperture 9 through which the needle 8 passes in order to cooperate with the loop taker (not shown) in the formation of stitches.

To hold the work against the throat plate 2 and feed dogs 4 there is provided the usual presser bar 10 slidably mounted in the head 6 for endwise movement and biased downwardly by spring means (not shown). The

2

presser bar 10 carries a presser foot 11 having a shank 12 that is secured to the lower end of the presser bar by a screw 13. The shank 12 includes a transverse plate 14 having a pair of spaced parallel depending flanges 15, Fig. 4. A main sole plate 16 is pivotally mounted on the shank 12 by means of a pair of pivot screws 17 threaded through the flanges 15 and having smooth surfaced stud ends 18 extending loosely through apertures in lugs 19 upstanding from the sole plate.

10 The bottom of the main sole plate 16 is provided longitudinally with a groove 20 to accommodate a chaining foot 21 having a sole plate 22 and an upstanding lug 23 extending loosely through an opening 16a in the main sole plate 16. The stud ends 18 of the pivot screws extend into recesses 24 in the opposite faces of the lug 23 pivotally to mount the chaining foot 21 on the shank 11. The recesses 24 are elongated to comprise a lost motion connection providing for bodily movement of the chaining foot 21 relatively to the shank 11 and main sole plate 16. The lug 23 is provided with a bore 25 in which is seated a coiled compression spring 26 that bears at one end against the bottom of the bore 25 and at the other end against the bottom of the transverse plate 14 of the shank 11. The feed dog 4 has a section 27, Fig. 2, cooperating with the chaining foot 21.

20 The spring 26 biases the chaining foot 21 bodily downwardly relatively to the main sole plate 16 as provided by the elongated recesses 24 and pivotally about the axis defined by the pivot screws 17. Pivotal movement of the chaining foot 21 relatively to the main sole plate 16 is limited by the binding of the lug 23 in the opening 16a in the sole plate through which it extends. With the pivotal movement of the chaining foot relatively to the sole plate stopped, the spring 26 will act to pivot 30 the heel of the sole plate 16 downwardly about the pivot axis, thus raising the forward portion or toe to facilitate the introduction of work. The pivotal movement of the main sole plate 16 is limited by the engagement of the top of the lugs 19 with the plate 14 as indicated in Fig.

30 40 3. In operation, the main sole plate 16 is forced downwardly by the presser bar spring to hold the work indicated at W, against the feed dogs and throat plate. The strength of the presser bar spring is relatively high so that the main sole plate 16 lies flat against the work with the spring 26 compressed. The chaining foot 21 also lies flat against the work and is freely movable bodily against the action of the spring 26 by virtue of the elongated recesses 24. With work passing through the machine, the main sole plate cooperates with the feed dog to feed the work. When the work passes from under the main sole plate, the enchain needle thread N and under thread U are held against the section 27 of the feed dog 4 by the chaining foot 21 under the relatively light action of the spring 26, the chaining foot 21 yielding bodily against the action of the spring 26 to accommodate the threads while the heavy pressure of the presser bar spring is absorbed by the engagement of the main sole plate 16 with the throat plate 2 and feed dogs 4.

45 55 60 When the presser bar 10 is raised to lift the presser foot 11 from the work, the spring 26 acts first to move the chaining foot 21 bodily until the stud ends 18 of the pivot screws 17 are seated in the top of the recesses 24, then acts to pivot the chaining foot until pivotal movement is limited by binding of the lug 23 in the opening 16a in the main sole plate through which it extends, and finally acts to pivot the main sole plate 16 to its stop position as illustrated in Fig. 3. In this construction, the spring 26 thus serves both as the bias for the chaining foot 21 and also as the bias for pivoting the main sole plate 16. At the same time, the sole plate 22 of the chaining foot 21 is flat against the section 27

of the feed dog and yields bodily to insure proper cooperation in the feeding of the thread chain.

Assembly of the presser foot in accordance with this invention comprises only inserting the spring 26 into the bore 25, placing the lug 23 of the chaining foot through the aperture 16a in the main sole plate, inserting the assembly between the flanges 15, and finally inserting the screws 17. The resultant device is very rigid, the flanges 15 being in face contact with the outer surfaces of the lugs 19 to hold and guide the main sole plate in pivoting.

Numerous alterations of the structure herein disclosed will suggest themselves to those skilled in the art. However, it is to be understood that the present disclosure relates to a preferred embodiment of my invention which is for purposes of illustration only and not to be construed as a limitation of the invention. All such modifications which do not depart from the spirit of the invention are intended to be included within the scope of the appended claims.

Having thus set forth the nature of the invention, what I claim herein is:

1. A presser foot for a sewing machine comprising a shank adapted to be secured to the presser bar of a sewing machine, a main sole plate, a chaining foot, common means for separately pivotally mounting said main sole plate and said chaining foot on said shank for pivotal movement of said chaining foot relatively to said main sole plate and said shank and defining a pivot axis, means providing for limited bodily movement of said chaining foot relatively to the pivot axis thereof, and spring means between said chaining foot and said shank for biasing said chaining foot bodily within the range of bodily movement and thereafter biasing said chaining foot pivotally about the pivot axis thereof, and means interconnecting said chaining foot and said main sole plate for pivotally biasing said main sole plate upon pivotal movement of said chaining foot.

2. A presser foot for a sewing machine comprising a shank adapted to be secured to the presser bar of a sewing machine, spaced depending flanges on said shank, a main sole plate having spaced upstanding lugs disposed between said flanges, a chaining foot having an upstanding lug disposed between the lugs of said main sole plate, pivot means associated with said flanges and said upstanding lugs for pivotally mounting said main sole plate and said chaining foot on said shank on a common pivot axis, and including a lost motion connection with said lug in said chaining foot to provide for limited bodily movement of said chaining foot relatively to the pivot axis, spring means between said chaining foot and said shank for biasing said chaining foot relatively to said shank, and means interconnecting said chaining foot and said main sole plate for pivotally biasing said main sole plate upon pivotal movement of said chaining foot.

3. A presser foot for a sewing machine comprising a shank adapted to be secured to the presser bar of a sewing machine, spaced depending flanges on said shank, a main sole plate having spaced upstanding lugs dis-

posed between said flanges, a chaining foot having an upstanding lug, said main sole plate having an aperture, said lug on said chaining foot extending loosely through said aperture in said main sole plate and disposed between the lugs of said main sole plate, said lug on said chaining foot having recesses in the opposite faces thereof, axially aligned pivot screws threaded through said flanges and having stud ends extending loosely through the lugs on said main sole plate and into said recesses, said recesses being elongated to provide for limited bodily movement of said chaining foot relatively to said pivot screws, spring means disposed between said chaining foot and said shank for biasing said chaining foot relatively to said shank, and means interconnecting said chaining foot and said main sole plate for pivotally biasing said main sole plate upon pivotal movement of said chaining foot.

4. In a sewing machine having a throat plate, a feed dog operable through said throat plate to advance the work, and a presser foot opposed to said throat plate and feed dog, said presser foot comprising a shank, spaced depending flanges on said shank, a main sole plate adapted to lie flat in engagement with said throat plate and feed dog and having spaced upstanding lugs disposed between said flanges, a chaining foot having a chaining sole plate adapted to cooperate with a section of said feed dog and having an upstanding lug, said main sole plate having an aperture, said lug on said chaining foot extending loosely through said aperture in said main sole plate and disposed between the lugs of said main sole plate, said lug on said chaining foot having recesses in the opposite faces thereof, axially aligned pivot screws threaded through said flanges and having stud ends extending loosely through the lugs on said main sole plate and into said recesses, said recesses being elongated to provide for limited bodily movement of said chaining foot relatively to said pivot screws in a direction toward and away from said feed dog, and spring means disposed between said chaining foot and said shank for biasing said chaining foot bodily toward said feed dog within the range of bodily movement of said chaining foot as determined by the elongated recesses and for pivotally biasing said chaining foot when said chaining foot is lifted from the work and said pivot screws are engaged against the end of the elongated recesses, said lug on said chaining foot engaging against the edges of the aperture in the main sole plate upon pivotal movement of said chaining foot relatively to said main sole plate to connect the same together for unitary pivotal movement.
